CLAIM

I claim the ornamental design for a study desk, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a study desk in a first embodiment, showing my new design;

FIG. 2 is a front view thereof;

FIG. 3 is a top view thereof;

FIG. 4 is a rear side view thereof;

FIG. 5 is a left side view thereof;

FIG. 6 is a right side view thereof;

FIG. 7 is a perspective view of a study desk in a second embodiment, showing my new design;

FIG. 8 is a front view thereof; and,

FIG. 9 is a rear side view thereof.
